UNITED STATES PATENT OFFICE.

HERRICK AIKEN, OF FRANKLIN, NEW HAMPSHIRE, ASSIGNOR TO CHARLES L. AIKEN,
OF FRANKLIN, NEW HAMPSHIRE.

KNITTING-MACHINE.

1,273,803.

Specification of Letters Patent. Patented July 30, 1918.

Application filed April 12, 1917. Serial No. 161,480.

To all whom it may concern:

Be it known that I, HERRICK AIKEN, of Franklin, in the county of Merrimack and State of New Hampshire, have invented certain new and useful Improvements in Knitting-Machines, of which the following is a specification.

This invention relates to knitting machines, and especially to the needle cylinder 10 and needles thereof.

For reasons which are so well known as not to require explanation herein, it is customary to slightly bend or curve the needles of knitting machines laterally so that there will be sufficient friction between their sides and the sides of the grooves in the cylinder in which the needles are reciprocally mounted, to cause the needles to remain in the positions to which they are shifted longitudinally until positively moved to some other position. The treatment of the needles to properly bend or curve them is a delicate one which is rendered unnecessary by my invention under which the necessary friction is effected by, or is the result of, magnetic action instead of by imparting to the needles forms other than straight or flat.

Of the accompanying drawings:

Figure 1 is a sectional elevation of so much of one type of knitting machine, with my improvements, as is necessary to explain my invention.

Fig. 2 represents a section on line 2—2 of Fig. 1.

It is to be understood that my invention is equally applicable to any other type of knitting machines, although the following description is limited to the embodiment illustrated in the two figures of the drawing.

The needle cylinder 10, having grooves for the needles 11 as usual, is mounted upon a suitable support a portion of which is indicated at 12. A circular series of magnets 13, wired in series and connected to a battery 14 or other source of electrical energy, are mounted in position close to the inner wall of the cylinder. A suitable support for said magnets is afforded by an inner shell 15 having a flange 16 by which said shell is securely mounted upon the support

12. The upper end of the shell flares outwardly, as at 17, whereby said shell not only provides a support for the magnets but also serves as a funnel or guide for the work that is being knitted. 55

When the knitting machine is in operation, and a proper current of electricity is flowing through the coils of the magnets, the needle cylinder itself becomes magnetized so that the needles are magnetically attracted to cause their inner edges to bear against the bottoms of the grooves in the cylinder 10 with sufficient pressure to cause the needles to remain in any position to which they have been shifted longitudinally 60 until positively moved to some other position. 65

Having now described my invention, and explained a way to carry the same into effect, although without attempting to describe obviously equivalent methods of producing the same results, what I claim is: 70

1. A knitting machine having magnets in proximity to the needle carrier for effecting friction between the needles and their 75 guides.

2. A knitting machine having grooved guideways for the needles, and means for magnetizing said guideways.

3. A knitting machine needle cylinder 80 having external grooves for the needles, and a series of electro-magnets adjacent the inner wall of the cylinder.

4. A knitting machine needle cylinder having external grooves for the needles, and 85 a series of electro-magnets adjacent the inner wall of the cylinder, a guide for the work being mounted inside said magnets.

5. A knitting machine needle cylinder having external grooves for the needles, a 90 shell having a flaring upper end inside the cylinder, and a series of electro-magnets supported by said shell in position to magnetize the cylinder.

In testimony whereof I have affixed my 95 signature.

HERRICK AIKEN.
